Primary Examiner — Celia Murphy*Assistant Examiner* — Darlington Ly(74) *Attorney, Agent, or Firm* — Stiennon & Stiennon(57) **CLAIM**

The ornamental design for a bicycle rack, as shown and described.

DESCRIPTION

FIG. 1 is a rear isometric view of the bicycle rack of my design;
 FIG. 2 is a left side elevation view thereof;

FIG. 3 is a front elevation view thereof;

FIG. 4 is a top plan view thereof;

FIG. 5 is a right side elevation view thereof;

FIG. 6 is a rear elevation view thereof; and,

FIG. 7 is a bottom plan view thereof.

The broken line showing of a pair of bolt holes is included for the purpose of illustrating environmental structure and forms no part of the claimed design.
